Primary Examiner — Philip S Hyder*Assistant Examiner* — Darlington Ly(74) *Attorney, Agent, or Firm* — James F. Hann; Haynes Beffel & Wolfeld LLP(57) **CLAIM**

The ornamental design for an automotive vehicle exterior, as shown and described.

DESCRIPTION

FIG. 1 is left side elevation view of an automotive vehicle exterior showing my new design, the right side elevation view being a mirror image;

FIG. 2 is a front, left side, top perspective view thereof;

FIG. 3 is a front elevational view thereof;

FIG. 4 is a rear elevational view thereof;

FIG. 5 is a rear, left side, top perspective view thereof; and,

FIG. 6 is a top plan view thereof.

The broken lines shown in the drawings illustrate portions of the automotive vehicle exterior that forms no part of claimed design.
